UNITED STATES PATENT OFFICE.

CHESTER A. BARNES, OF BLUE GRASS, IOWA.

PORTABLE FEED-MIXING APPARATUS.

1,279,221.

Specification of Letters Patent. Patented Sept. 17, 1918.

Application filed January 26, 1917. Serial No. 144,732.

To all whom it may concern:

Be it known that I, CHESTER A. BARNES, a citizen of the United States, residing at Blue Grass, in the county of Scott and State of Iowa, have invented new and useful Improvements in Portable Feed-Mixing Apparatus, of which the following is a specification.

The present invention relates generally to a portable feed mixing apparatus for stock.

In carrying out my invention it is my purpose to arrange upon a suitable truck a tank or chamber having revoluble blades arranged therein and operative from the exterior of the said tank whereby to effectively mix the feed for stock deposited in the said tank, and to provide means whereby a desired quantity of the said contents may be fed from the tank at desired intervals.

It is my purpose to produce in combination with a wheeled device for mixing the feed of swine, a discharge or outlet pipe of a novel construction and arrangement whereby the same, when turned to one position will prevent the discharge of the feed and when turned to another position will permit of the outflow of the feed from the tank device.

It is a further object of the invention to produce a device of this character which shall be of a comparatively simple construction but strongly built so as to withstand rough usage, while at the same time, the same can be manufactured and marketed at a nominal price and which shall be thoroughly efficient for the purpose for which it is devised.

With the above and other objects in view the improvement resides in the construction, combination and arrangement of parts set forth in the following specification and falling within the scope of the appended claims.

In the drawings:

Figure 1 is a side elevation of a device constructed in accordance with the present invention,

Fig. 2 is a front elevation of the same,

Fig. 3 is a rear elevation illustrating, by the dotted lines, the position of the discharge or outlet pipe, when the feed is to be delivered to the mixing and containing tank,

Fig. 4 is a horizontal sectional view approximately on the line 4-4 of Fig. 1.

In the construction of the portable mixing apparatus to which my improvement is ap-

plied I have illustrated a running gear preferably constructed of metal, the front and rear wheels 3 and 4 respectively being journaled on axles 1 and 2 respectively that are secured to substantially U-shaped yokes 5 and 6 respectively. The yokes support a skeleton frame including corner members 15 and longitudinal connecting members 16. The skeleton frame is arranged at an inclination, and a fifth wheel 10 is arranged between the yoke 5 and the skeleton frame, a pivot 11 passing through the disks comprising the fifth wheel. The axles may be connected by a reach bar 7 which is pivotally secured as at 8 to the front axle 1, and on the front axle 1 is a hound 12 carrying a pole 13.

In the showing of the drawings the frame supports a trough 19 having an open top normally closed by a suitable door, and within the trough is arranged a series of mixing blades having the shaft therefor journaled in suitable bearings and projecting through one of the ends of the trough. The end of the shaft, which is indicated by the numeral 45 may have secured thereto a toothed wheel 52 that is engaged by a pinion 54 secured on a shaft 51, and to the shaft 51 is keyed or otherwise connected the operating handle 55. The toothed wheels and shafts therefor may include a suitable casing 50.

The rear face or plate of the tank or trough at the lower edge thereof, and in a line with the central portion of the rounded bottom of the said trough is provided with an outlet pipe 30, which is arranged at the same inclination as that of the said trough and which has its outer end supported by an angularly arranged strap 31 that is secured to the referred to rear plate of the trough. To the end of the pipe 30 is connected, for rotatable movement on the said pipe, an elbow pipe 32, a suitable packing being arranged between the joint of the said elbow and the end of the said outlet pipe to insure a water tight connection between these elements, and connected with the elbow is a discharge pipe or spout 33. The numeral 34 designates a suitable clip that is secured around the discharge pipe or spout 33, and this clip is formed with an inwardly extending stud 35 that has its outer end capped or enlarged, as at 36, and which stud is adapted to receive a substantially U-shaped member or bail 37 which is secured to an angular element 38 upon one end of a longitudinally

arranged shaft 39. The shaft 39 is journaled in suitable bearing openings provided in bracket members 40 that may be formed by bending the ends of the horizontal bars 5 of the frame at the rear of the said frame and by extending the lower connecting bar at the front of the frame, and the shaft is prevented from longitudinal movement through the medium of suitable collars arranged thereon to the opposite sides of the rear bracket 40. The outer end of the shaft 39 has secured thereto the angular end 40 of a lever 42, the said lever being of a length to project above the top of the trough, and 10 the numeral 43 designates a catch, in the nature of a substantially U-shaped bail which is hingedly secured to the top plate of the trough and which is adapted to be swung over the cover plate 21 to engage with the opposite edges of the lever 42 to hold the 15 said lever in a vertical position, and likewise to retain the discharge pipe or spout 33 in an upwardly disposed vertical position to prevent the outflow of the contents of the trough therethrough. It will be apparent 20 that when the lever is released from the catch 43 and swung outwardly of the device that the discharge pipe or spout 33 may be swung with the elbow 32 at a desired angle 25 with respect to the tank, whereby to permit of the free outflow of the feeding material from the inclined tank.

The arrangement of the outlet means just described is highly desirable in a construction of this class inasmuch as the spout or pipe 33 may be properly directed to the feeding trough for the swine so that the material from the tank or trough 19 can thus be delivered without necessitating the same 30 being conveyed therefrom to pails or buckets

Copies of this patent may be obtained for five cents each, by addressing the "Commissioner of Patents, Washington, D. C."

as would be necessary if an ordinary valved outlet was provided.

Having thus described the invention, what I claim is:

1. In an outlet pipe for mixing troughs, a 45 swiveled discharge spout for the outlet pipe, a lug upon said spout, a yoke member engaging with the lug, a shaft arranged longitudinally of the frame and journaled in bearings upon the said frame and connected to 50 the said yoke, an angular-operating handle for the shaft, and a catch member upon the trough adapted to engage with the handle to retain the same in one position and the outlet spout in an upward vertical position 55 with respect to the trough.

2. In an outlet pipe for mixing troughs, a discharge tube having an elbow swiveled to the outlet pipe, a stud on said spout, a yoke engaging the stud, a longitudinally arranged 60 shaft connected with the yoke, an angular handle secured to the shaft, and a swinging substantially U-shaped catch member adapted to engage with the opposite edges of the handle to retain the same in a position to 65 hold the outlet spout in an upward vertical position.

3. In an outlet spout for mixing troughs, a discharge pipe swiveled thereto, a shaft journaled in bearings on the side of the 70 trough, a yoke member secured to one end of the shaft, a stud on the swiveled pipe engaged by the yoke, an angular lever secured to the outer end of the shaft and means on the trough co-engaging with the lever for 75 holding the same in one position and the swiveled pipe likewise in one position.

In testimony whereof I affix my signature.

CHESTER A. BARNES.
